United States Patent Office.

JAMES S. ZANE, OF PLEASANT PLAINS, ILLINOIS.

Letters Patent No. 71,111, dated November 19, 1867.

IMPROVED SNOW-PLough.

The Schedule referred to in these Letters Patent and making part of the same.

TO ALL WHOM IT MAY CONCERN:

Be it known that I, JAMES S. ZANE, of Pleasant Plains, in the county of Sangamon, and State of Illinois, have invented a new and useful improvement in Snow-Ploughs; and I do hereby declare that the following is a full, clear, and exact description thereof, which will enable others skilled in the art to make and use the same, reference being had to the accompanying drawings, forming part of this specification.

Figure 1 is a side view of my improved snow-plough, with the wings raised to their highest elevation.

Figure 2 is a back view, showing the mechanism for raising and lowering the wings.

Figure 3 is a top view of the plough on the outside.

Figure 4 is top view of the elevating mechanism detached.

Similar letters of reference indicate corresponding parts.

This invention relates to an improvement in the construction of snow-ploughs for railroads, and consists in inclined planes which are mounted on a truck and rise from the bed of the road to an elevated double mould-board, which is hinged and so arranged in combination with machinery that it may be raised and lowered as required.

A A, figs. 1, 3, represent inclined planes made of sheet iron or other suitable material, and secured on a truck, B, mounted on wheels C C, adapted to the rails of a railroad, and designed to be attached in front of a locomotive for removing the snow from the track. The inclined planes A A are united lengthwise in the middle to form a sharp ridge between them, and face towards both sides of the track. They rise from the bed of the road to a double mould-board, D, elevated several feet above the level of the track, and hinged upon the truck-frame so as to be raised and lowered as desired. The elevated double mould-board D is intended for clearing away deep snow-drifts, and it is arranged so as to be lowered out of the way of bridges when passing under them. For this purpose it is attached to two segmental racks, E E, engaging the pinions *a a* on a shaft, *b*, that carries a pulley, *c*, connected by a band to a pulley, *c'*, placed on the axle *m* of the rear track-wheels C C, fig. 2. When the double mould-board D is raised, the lower ends of the segmental racks E E rest upon spring supports *g g*, connected with a lever, *h*, fig. 4, by which they are drawn aside from under the racks to allow them to be lowered when necessary.

To operate the pinions *a a* for raising or lowering the double mould-board D, a shifting-clutch, *k*, is placed on the axle *m* to engage the pulley *c'* by means of a lever, *h'*. The levers *h h'* may be worked by means of ropes connecting them with the engine. At the front end of the snow-plough are placed two vertical cutters, *s s*, at the sides secured to a frame, *n*, and a central movable cutter, *p*, which cutters divide the mass of snow and allow it to be thrown on each side of the track.

Having thus described my invention, what I claim as new, and desire to secure by Letters Patent, is—

1. The double mould-board D, hinged at the upper end of the inclined planes A A, to be raised and lowered as and for the purposes herein described.
2. The arrangement of the inclined planes A A, forming a ridge in the middle, the vertical cutters *s s*, and the movable cutter *p*, substantially as described.

JAMES S. ZANE.
